UNITED STATES PATENT OFFICE

FRED L. MILLS, OF OAK PARK, ILLINOIS, ASSIGNOR TO MILLS NOVELTY COMPANY, OF CHICAGO, ILLINOIS, A CORPORATION OF ILLINOIS

COMMODITY VENDING MACHINE

Application filed January 20, 1930. Serial No. 421,880.

This invention relates to vending machines and has for its purpose the provision of a machine particularly adapted to the vending of staple commodities such as groceries or other 5 merchandise now commonly sold by clerks in grocery stores or like places.

One of the objects of the invention is to provide a machine of this character which is highly flexible in that certain of the parts 10 may be readily interchanged to adapt the machine for containing different types and quantities of articles and to be operated by coins of different denominations.

A further object of the invention is to provide a machine of the kind described which may be used as a show-case in which the articles are visible to the customer and from 15 which he may obtain them by simple manipulation of a coin slide or other device for operating the machine through the instrumentality of a coin.

Other objects and advantages of the invention will be apparent as it is better understood from the following description, which, 20 taken in connection with the accompanying drawings, discloses a preferred embodiment thereof.

Referring to the drawings,

Fig. 1 is a front elevation of a vending machine in which my invention is embodied;

Fig. 2 is a top plan view thereof, with a portion of one of the drums broken away for convenience in illustration;

Fig. 3 is a vertical sectional view, taken substantially on the section line 3—3 in Fig. 2;

Fig. 4 is a front to back sectional view, taken substantially on the section line 4—4 in Fig. 1;

Fig. 5 is a plan view of a double coin slide 40 which may be used in the machine in case two coins are required for operating it;

Fig. 6 is a longitudinal sectional view of said slide;

Fig. 7 is an enlarged partial front to back 45 section showing the means by which the cups or other receptacles are secured within the drum and the means by which the drum is released for rotation;

Fig. 8 is a sectional view of the central portion of one of the drums and associated parts,

showing the spring for rotating the drum and the clock mechanism by means of which the rotation is controlled; and

Fig. 9 is a sectional view of the outer part of one of the drums and of one of the receptacles carried thereby, showing the latching device for limiting the rotation of the drum.

The apparatus shown in the drawings, which is to be considered as merely an illustrative embodiment of the invention, is enclosed within a casing 21 having front windows 22 and being equipped with delivery trays 23 and coin slides 24, all of which parts are clearly shown in Fig. 1. The casing is provided with a base 25 adapted to rest upon a counter or other suitable support, the machine by reason of the windows 22, or other suitable means for displaying the contents, being adapted to be used as a show case as in a grocery store or like place.

Drums 26, of which three are shown in the drawings, are rotatably mounted within the casing 21, said drums, as shown, being mounted upon fixed shafts 27 having bearings in uprights 28 rising from a plate 31 secured by screws 32 to the base 25 (see Fig. 3). Arcuate covers 33 are provided in the top of the casing, one for each of the drums 26, and are hinged at 34 (see Fig. 2), said covers being provided with locks 35 for which the proprietor of the store, or other authorized person, may have a key, the covers being adapted to be lifted to permit the filling of the machine with commodities to be dispensed, as will presently appear.

Shells 36 are provided in the casing enclosing the lower part of the drum to prevent the discharge of the contents except through a chute 37 positioned adjacent an opening 38 in the shells and leading to the tray 23 to which the articles are adapted to be delivered after operation of the machine, as will later be described.

The opposite side plates of the drum 26 are provided with a series of registering notches 39 and with spring clips 41 secured to said plates at 42 and disposed adjacent said notches 39. Said clips consist of two opposed spring members, the central portions of which are oppositely concaved and the

ends of which are flared outwardly to provide jaws into which pins 43 on cup members or containers 44 may be inserted, the cups being held in place between the side plates of the drum by the clamping action of said clips 41 upon pins 43. The drum is rotatable as will later appear and serves as a carrier for the cups or containers to present them successively to a point of discharge.

10 As shown in Fig. 7, the cups 44 may be varied in size and cups of different size are interchangeable, thus contributing materially to the flexibility of the machine. Ordinarily, perhaps, cups of one size would be used in one drum, but it will be manifest that with the clips 41 uniformly spaced and arranged close together, cups of one size may be readily substituted for those of another, and cups of different sizes may be placed in 15 the same drum if desired. The latter arrangement may be desirable to permit the proprietor to give prizes by increasing the contents of certain of the cups, thus encouraging the patronage of the machine. Said 20 cups are adapted to contain the commodity or commodities to be dispensed which may be either in package form or loose, the contents being shown in the drawings as packages 45. The contents of the packages are 25 indicated in Fig. 1 by legends on the packages themselves, although, of course, other means of identification may be employed if desired. Different commodities are contained within each of the three drums, as 30 shown in Fig. 1, and of course the machine might be provided with any desired number 35 of drums.

On the interior of each of the drums 26 surrounding the shaft 27 is a cylinder 46 containing a spring 47, one end of which is secured to the shaft 27 about which the spring is wound and the other end to the cylinder, as indicated at 48 in Fig. 7. This spring serves to rotate the drum 36 when the latter 45 is released in manner which will presently be described.

A clock, or governor, mechanism is provided to control the rotation of the drum under the influence of the spring 47, such 50 mechanism being shown in Figs. 3 and 8 and comprising a large gear 49 upon the shaft 27, said gear meshing with a pinion 51 upon a stud 52 in the frame upright 28, said stud also carrying a gear 53 meshing with a pinion 54 carried upon a stud 55 mounted in the frame 28, said stud also carrying a gear 56 meshing with a pinion 57 carried by a stud 58 journaled in arms 59 and 61 at the upper end of the frame upright 28, said stud 58 also 60 carrying a vane 62 acting as a governor in manner which will be readily understood.

The mechanism just described serves to prevent the drums from jumping under the influence of the springs 47 and causes them 65 to turn at an appropriate rate of speed.

One of the pins 43 on each of the cups 44 is elongated, as shown in Fig. 9, and is adapted to engage a latch member 63 pivoted at 64 to the outside of one of the walls of the chute 37, said latch having a tail part 65 normally held in engagement with a fixed stud 66 on said wall by means of a spring 67 secured at one end to the wall and at the opposite end to said tail part 65 of the latch member 63, said parts being shown in dotted lines in Fig. 7. If the cup 44 is of such size as to be provided with more than one pair of the pins 43, the elongated one will be one of the last pair, considering them in the order that they reach the passageway 37 during the rotation of the drum. With the parts in normal position, as shown in Fig. 7, said elongated pin will be held against the latch 63 by the tension of the spring 47, said latch, however, being prevented from turning by means of a detent 68 pivoted at 69 to the wall of the chute 37 and having a shoulder 71 engaging the tail part 65 of said latch 63, said detent being held in the normal position shown in Fig. 7 by means of a spring 72 secured at one end to the outer end of said detent and at the other end to the wall of the chute. A rod 73 is connected with said detent at 74 and extends upwardly into engagement with a coin-operated lever 75 which is pivoted at 76 to depending ears 77 on the coin slide 24, the upper end of said rod being pointed and being disposed in a socket 78 in said lever 75. Said lever 75 is adapted to be actuated by means of a coin inserted in the appropriate slide 24 for the drum to be actuated, and, for an illustration of the construction of the slide, attention is called to Figs. 5 and 6.

The slides may be either single or double, those for the two end drums being shown as single and that for the middle drum as double, as may be seen from viewing Fig. 2. Double slides and single slides for coins of different denomination may all be of the same size and adapted to be interchangeably fitted in the slide openings in the casing to which they are locked as shown in Figs. 1, 4 and 7.

The slides consist of a fixed plate 79 mounted in the casing 21 and having surrounding flanges 81 disposed above a slidable plate 82 mounted upon said plate 79 and being provided with a coin receiving opening 83, a slot 84 and a finger-piece 85 by means of which it is adapted to be moved in and out to actuate the machine through the instrumentality of the coin inserted in the opening 83. When the slide 82 is moved all the way inwardly, the coin passes through an opening 86 in the plate 79, and the forward edge thereof drops upon the top of an arm 87 on the lever 75 which is of bell crank form, the top of said arm being provided with a shoulder 88 upon which the coin acts

during the final inward movement of said slide, thus rocking the lever 75 about the pivot 76 and moving the rod 73 downwardly. A pivoted dog 89 is provided above the opening 86, being pivoted to ears 91 upon a top plate 92 rigid with the plate 79. A leaf spring 93 is secured to the plate 92 by means of screws 94 and tends to urge the dog 89 downwardly, causing the latter to hold the coin in proper relation to the lever 75 to cause the latter to be actuated thereby. A pin 95 is provided in the plate 79 and disposed within the slot 84 of the slide 82 to guide the latter in its movement. A dog 95' pivoted at 96 to an ear 97 secured to the member 92 is urged downwardly by means of a spring 98 secured by a screw 99 to said member 92 and serves to prevent complete forward movement of the slide 82 in the event that no coin has been placed in the opening 83, said dog normally resting upon the forward end of the plate 82, as shown in Fig. 6, and being adapted to move through said opening 83 and through an opening 101 in the plate 79 to the dotted line position shown in said Fig. 6, in which it will obviously obstruct the movement of said slide 82.

It may be that the price of the article to be dispensed will be such as to require the use of two coins, such as a nickel and a dime for an article costing fifteen cents. In such case, a double slide may be employed, such as that shown in Fig. 5, in which two openings 83 are provided of different size, there being in such case separate dogs 95' and 89 for each of the openings and it being apparent that the slide can not be operated unless there is a coin in each of the openings. At the end of the inner stroke of the slide 82, the coin will pass through the opening 86 and upon return of the lever 75 to the position shown in Fig. 6, the coin will be discharged from the top of the arm 87 into a receptacle or coin box (not shown).

Referring again to Fig. 7, it will be noted that the downward movement of the rod 73 will disengage the shoulder 71 of the detent 68 from the tail part 65 of the latch member 63 which will then be turned in counter-clockwise direction by reason of the fact that the spring 47 is stronger than the spring 67 and the pressure of the elongated pin 43 is thus sufficient to overcome the resistance of said last mentioned spring. As soon as the pin 43 has passed, however, said spring 67 will restore the latch to the position shown in Fig. 7 and by the time the next elongated pin 43 comes against the latch, the detent 68 will have been restored to normal position by means of the spring 72 and the latch will be held thereby against further movement until said detent is released by the insertion of another coin. The movement of the drum 26 permitted upon each actuation of the ma-

chine is just sufficient to bring one additional cup 44 into position above the chute 37 into which the contents of the cup are discharged. The empty cups may be refilled by the proprietor by opening the covers 33 and rotating the drum so as to present the empty cups at the top of the machine and he will, of course, upon such occasions, rotate said drum sufficiently to rewind the spring 47 which will have sufficient tension to rotate the drum 75 through one complete revolution.

As has been previously pointed out, the cups or receptacles 44 carried by the drum may be interchanged as desired according to the commodity to be dispensed, and since the slides 24 may be interchanged to provide for the operation of any particular drum with the amount of money which may be the price of the articles contained in the drum, the machine is extremely flexible and well adapted to conditions of commercial use.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. A vending machine comprising a movable carrier, a plurality of commodity containers attachable to said carrier, a discharge chute, and coin-controlled means for moving said carrier to successively bring said containers into position for discharge of the contents thereof through said chute, said carrier being equipped with means for attachment thereto of containers which vary in dimension in the direction of movement of the carrier, and said containers having means associated therewith for controlling said carrier moving means to produce successive movements of the carrier in accordance with the size of the container to be discharged.

2. A vending machine comprising a carrier drum, a spring for rotating said drum, said drum having flanges provided with spaced retaining members, a plurality of commodity containers of sizes which vary with respect to their peripheral span on the drum, said containers being equipped with means adapted to cooperate with said retaining members to removably secure the containers within the drum, a latch for normally holding said drum against rotation, a discharge chute, coin controlled means for releasing said latch to permit the drum to rotate under the influence of said spring, and means associated with said containers for controlling the rotation of the drum whereby each movement of the latter brings a filled

container into position for discharge of the contents thereof through said chute.

3. A vending machine comprising a rotatable carrier drum having flanges equipped with registering notches, spring clips being attached to the drum adjacent said notches, a plurality of interchangeable commodity containers of varying sizes, said containers having means for engaging said clips to removably secure the containers to the drum, a discharge chute adjacent said drum, and coin-controlled means for moving the drum with a step motion to bring one of said containers into position for discharging the contents thereof into said chute upon each coin actuation of the machine.

4. A vending machine comprising a rotatable carrier drum, a plurality of commodity containers removably attachable to said drum, a discharge chute adjacent the drum, coin-controlled means for moving the drum with a step motion to bring one of said containers into position to discharge the contents thereof into said chute upon each coin actuation of the machine, attaching devices whereby containers of sizes which vary with respect to their peripheral span on the drum may be interchangeably attached to the drum, and means for limiting the movement of said carrier drum so that the movement in each instance is proportional to the size of the container to be discharged.

5. A vending machine comprising a rotatable drum, a spring for rotating said drum, a plurality of commodity interchangeable containers removably attachable to said drum, said containers being of sizes which vary with respect to their peripheral span on the drum and each having a projecting stop pin thereon, a latch normally engaging said pin, and coin-controlled means for releasing said latch upon the insertion of a coin into the machine to permit an advance of said drum under the influence of said spring, such advance bringing one of said containers into position to discharge the contents thereof from the machine.

6. A vending machine comprising a rotatable drum, a spring for rotating said drum, a plurality of commodity containers carried by the drum, each of said containers having a projecting stop pin thereon, a latch normally engaging said pin, coin-controlled means for releasing said latch upon the insertion of a coin into the machine to permit an advance of said drum under the influence of said spring, such advance bringing one of said containers into position to discharge the contents thereof from the machine, and means for restoring the latch after actuation to position to be engaged by the pin on the next succeeding container, said coin-controlled means holding said latch in such position until the next coin actuation of the machine.

7. A vending machine comprising a rotatable drum, a spring for rotating said drum, a plurality of commodity containers removably attachable to said drum, said containers being of sizes which vary with respect to their peripheral span on the drum, a stop pin associated with each of said containers, a latch normally engaging said pin, and coin-controlled means for releasing said latch upon the insertion of a coin into the machine to permit an advance of said drum under the influence of said spring, such advance bringing one of said containers into position to discharge the contents thereof from the machine.

8. A vending machine comprising a rotatable drum, a spring for rotating said drum, a plurality of commodity containers carried by the drum, a stop pin associated with each of said containers, a latch normally engaging said pin, coin-controlled means for releasing said latch upon the insertion of a coin into the machine to permit an advance of said drum under the influence of said spring, such advance bringing one of said containers into position to discharge the contents thereof from the machine, and means for restoring the latch after actuation to position to be engaged by the pin on the next succeeding container, said coin-controlled means holding said latch in such position until the next coin actuation of the machine.

9. In a coin-controlled vending machine a carrier drum equipped with interchangeable commodity containers of varying sizes, a spring for rotating said drum; means controlled by said commodity containers to produce successive movements of the drum under the influence of said spring, means for limiting the movements of the drum so that each movement shall be proportional to the size of the container to be discharged, and clock mechanism for controlling the rotation of the drum under the influence of said spring.

10. A vending machine comprising a movable carrier, a plurality of commodity containers removably attachable to said carrier, attaching devices on the carrier whereby containers of sizes which vary in dimension in the direction of movement of the carrier may be interchangeably attached to the carrier, coin-controlled means for moving said carrier with a step motion for each coin actuation, means for limiting the movement of said carrier upon any particular actuation of the machine so that such movement shall be proportional to the size of the container to be discharged and will present such container in position for removal of the contents thereof from the machine, a coin slide, a coin actuated mechanism operable by a coin in said slide, said mechanism being operable by coins of different denomination determined by the coin slide employed, and the machine being

adapted to have coin slides for different coins interchangeably applied thereto.

11. A vending machine comprising a carrier drum having flanges equipped with registering notches, spring clips attached to the drum adjacent said notches, a plurality of commodity containers having pins thereon adapted to be inserted within and clamped by said clips to hold the containers in the drum, one of the pins on each of said containers being elongated and serving as a stop pin, a latching device mounted adjacent the drum and cooperating with said pin, a spring for rotating said drum, means for holding said latch normally in engagement with one of said stop pins, and coin actuated means for releasing said latch to permit the drum to advance until the latch is engaged by the next succeeding stop pin, such movement presenting one of said containers to position for removal of the contents thereof from the machine.

12. In a coin-controlled vending machine, a movable carrier equipped with commodity containers which vary in dimension in the direction of movement of the carrier, means for moving said carrier, means for releasing said carrier to cause the same to successively present said containers to a discharge station, and means for stopping the movement of the carrier so that in each instance the movement shall be proportional to the size of the container next to be discharged.

13. In a coin-controlled vending machine, a movable carrier equipped with interchangeable commodity containers which vary in dimension in the direction of movement of the carrier, means for moving said carrier, means for releasing said carrier to cause the same to successively present said containers to a discharge station, and means for stopping the movement of the carrier so that in each instance the movement shall be proportional to the size of the container next to be discharged.

14. In a coin-controlled vending machine, a movable carrier equipped with interchangeable commodity containers of varying sizes, and means controlled by said commodity containers to produce successive movements of the carrier in accordance with the size of the container to be discharged.

In witness whereof, I hereunto subscribe my name to this specification.

FRED L. MILLS.
